UNITED STATES PATENT OFFICE.

GEORGE BENJAMIN LINDSAY, OF KOKOMO, INDIANA.

SHARPENING DEVICE.

Application filed July 9, 1921. Serial No. 483,440.

To all whom it may concern:

Be it known that I, GEORGE BENJAMIN LINDSAY, a citizen of the United States, resident of Kokomo, county of Howard, and 5 State of Indiana, have invented new and useful Improvements in Sharpening Devices, of which the following is a specification, the principle of the invention being herein explained and the best mode in which I have 10 contemplated applying that principle, so as to distinguish it from other inventions.

My invention relates to sharpening devices adapted to sharpening disk harrow blades or the like. The object of the invention is to provide a device of the above described character which may be mounted upon a harrow and so arranged as to exercise its sharpening function during the ordinary operation of the harrow.

20 The said invention consists of means hereinafter fully described and particularly set forth in the claims.

More specifically, the invention comprises a suitable sharpener frame which carries an 25 abrading member, together with an auxiliary frame-bar which may be detachably secured to the harrow frame adjacent to the disk, the arrangement being such as will permit the sharpening device to be secured at 30 various positions along said bar, whereby its sharpening function may be directed to any one of the disks which may require such sharpening.

The annexed drawings and the following 35 description set forth in detail certain means embodying my invention, the disclosed means, however, constituting but one of the various mechanical forms in which the principle of the invention may be applied.

40 In said annexed drawings:

Figure 1 represents a plan of a disk harrow to which my invention has been applied;

Fig. 2 represents, upon an enlarged scale, a front elevation of the sharpening device;

45 Fig. 3 represents, upon such enlarged scale, a side elevation of said device, a part of one jaw being broken away to disclose an abrading member and its mounting;

Fig. 4 represents a section taken upon the 50 plane indicated by the line IV—IV, Fig. 3;

Fig. 5 represents a section taken upon the plane indicated by line V—V, Fig. 3; and

Fig. 6 represents a detail section taken 55 upon the plane indicated by the line VI—VI, Fig. 4.

The illustrated embodiment of my inven-

tion includes a frame-bar 1, Fig. 1, which is detachably securable by means of suitable bolts 2 to any one of the cross-members 3 forming part of the auxiliary harrow frame 60 upon which the disks are directly mounted. This bar when secured in place as shown, extends backwardly and parallel with the disk axis, and is provided with a multiplicity of holes 4, two of these holes being 65 located above and adjacent to the rear portion of the periphery in each disk. These holes are adapted to receive the upper ends of two angle rods 5—5, Figs. 2 and 3. The upper ends of the vertical members of rods 70 5—5 are threaded and provided with the jam-nuts 6—6. These upper ends are securable to bar 1 by means of thumb-nuts 7 co-operating with the jam-nuts 6.

The ends of the horizontal members of 75 rods 5—5 are flattened as at 8, Figs. 3 and 4, and are bolted to opposite sides of a block 9 through which extends vertically a pivot pin 10. This pin forms a journal for two jaws 11 and 12. The horizontal arms of the 80 rod 5 extend as shown in Fig. 1, backwardly and perpendicularly to the frame bar 1.

Intermediate of their ends and in these jaws are formed two apertures through which extends a bolt 13, whose ends are 85 threaded and provided with nuts 14—14. Intermediately of these nuts and around the bolt, are interposed two coiled springs 15—15 whose inner ends bear against the outer surface of the jaws and whose outer 90 end surfaces bear against the nuts 14. These nuts may therefore be adjusted so as to cause the coil springs to actuate the outer or free ends of the jaws toward each other. The outer or free end of jaw 11 is formed with 95 a bifurcated boss 16 in the open space of which is mounted a carrier 17 for the cutting member 18 consisting preferably of an ordinary file of a character suitable for cutting the periphery of a harrow disk. This 100 carrier 17 is pivotally secured in this boss by means of pivotal screw-pins 19—19, as shown in Figs. 3 and 4, and consists of a block provided with a rectangular way 20 into which the cutting member or file 18 105 may be inserted, its position in this way being secured by means of a set screw 21, shown in dotted lines in Fig. 4.

The jaw 11 is furthermore provided with a laterally extending boss 22 in which is 110 mounted an oscillatory pin 23, Figure 6. This pin is provided with a threaded open-

ing 24 which is engaged by a screw 25 having its outer end provided with a thumb-piece 26 and also passing through a laterally enlarged opening 27 formed in the boss. 5 It will be noted that the screw may, as a result of the above described structure, have a limited amount of oscillation imparted to it. The inner end of this screw articulates with a boss 28 formed upon the block 17, 10 being longitudinally secured therein by means of a pin 29 engaging a groove 30 formed in the engaging end of said screw, also as clearly shown in Fig. 6.

By turning the screw 25, it will be seen 15 that the block 17 and hence the cutting member 18 may be adjusted upon their common axis of oscillation.

The outer or free end of the other jaw 12 is also provided with a bifurcated boss 20 31 in which is mounted an anti-friction roller 32 having an axis at right angles with the axis of oscillation of the block 17.

The above described device is secured in 25 the desired position upon the bar 1, the nuts 14 having first been turned so as to permit the jaws 11 and 12 to become separated so as to allow their outer ends to enclose the adjacent harrow disk. The nuts 14 now being turned so as to compress the springs 15—15, 30 the jaws close until the anti-friction roller 32 comes into contact with the concave side of the disk and the cutting member 18 into contact with that portion of the disk's periphery which it is desired to cut and so 35 effect the required sharpening. The screw 25 is turned so as to impart to the cutting member the desired angular position, all as will be readily understood by those skilled in the art.

40 In addition to the above described parts, I have also provided a resilient member 33,

which is secured to that side of the block 9 adjacent to the jaw 11, by means of suitable screws 34, Fig. 2, and whose outer end portion is adapted to lie against the convex side of the disk, as shown in Fig. 4, and act as a scraper for removing earth from such concave side of said disk, thus keeping such earth from clogging the cutting member and interfering with the sharpening operation. 45

50 What I claim is:

1. A disk-sharpening device comprising the combination of a suitable frame-member; two relatively movable jaws mounted upon the latter; an abrading member pivotally mounted upon one of said jaws; means tending to close the latter; and means for adjusting said abrading member upon its pivotal axis. 55

2. A disk-sharpening device comprising the combination of a suitable frame-member, two jaws pivotally mounted upon the latter, an abrading member pivotally mounted upon one of said jaws, an anti-friction roller mounted upon the other of 60 said jaws, means tending to close the latter, and means for adjusting said abrading member upon its pivotal axis. 65

3. A disk sharpening device comprising the combination of a suitable support; a block secured to said support; two jaws pivotally mounted upon the same block; a cutting member oscillatorily mounted in the free end of one of said jaws so as to permit it to be moved toward and from the other jaw end; a pivotally mounted adjusting screw carried by the jaw upon which said cutting member is mounted, and having one end engaging the latter; and means tending to close said two jaws. 70

80 Signed by me this 23 day of June, 1921.
GEORGE BENJAMIN LINDSAY.
